UNITED STATES PATENT OFFICE.

FRANZ YOKEL, OF MERIDEN, CONNECTICUT, ASSIGNOR TO THE MERIDEN BRONZE COMPANY, OF SAME PLACE.

DESIGN FOR A LAMP-FOUNT HOLDER.

SPECIFICATION forming part of Design No. 23,778, dated November 6, 1894.

Application filed October 9, 1894. Serial No. 525,437. Term of patent 3½ years.

To all whom it may concern:

Be it known that I, FRANZ YOKEL, of Meriden, in the county of New Haven and State of Connecticut, have invented a new and original 5 Design for a Lamp-Fount Holder; and I do hereby declare the following, when taken in connection with the accompanying drawing and the letters of reference marked thereon, to be a full, clear, and exact description of the 10 same, and which said drawing constitutes part of this specification and represents a perspective view.

This invention relates to a design for a holder for lamp-founts, and consists in the 15 configuration and ornamentation as shown in the accompanying illustration.

The body of the holder is of bowl-shape, its lower end contracted toward the base. The ornamentation of the bowl consists of a series 20 of large foliated scrolls A, springing from the contracted base B, branching upward and encircling a shell C and scroll ornamentation D, the neck or contracted upper end E of the bowl extending down and meeting the scrolls of the bowl. This band or neck is solid, and 25 ornamented by a series of substantially circular shields F. The upper edge of this band or neck is rolled outward in a series of irregular overlapping scallops, and is surmounted by a series of circumferentially arranged open 30 scrolls G, all as shown in the accompanying illustration.

I claim—

The design for a lamp-fount holder as herein shown and described. 35

In testimony whereof I have signed this specification in the presence of two subscribing witnesses.

FRANZ YOKEL.
